UNITED STATES PATENT OFFICE.

EDWARD C. MEIER, OF PHOENIXVILLE, PENNSYLVANIA.

DESIGN FOR A HAND-HOLE PLATE.

47,931.

Specification for Design.

Patented Oct. 5, 1915.

Application filed July 14, 1915. Serial No. 39,933. Term of patent 14 years.

To all whom it may concern:

Be it known that I, EDWARD C. MEIER, a citizen of the United States, residing at Phoenixville, in the county of Chester and State of Pennsylvania, have invented a new, original, and ornamental Design for Hand-Hole Plates, of which the following is a specification, reference being had to the accompanying drawing, forming a part thereof.

Figure 1 is a view in front elevation of a

hand-hole plate, showing my new design. Fig. 2 is a plan view of the article shown in Fig. 1, and Fig. 3 is a view in rear elevation.

I claim:

The ornamental design for a hand-hole plate as shown.

EDWARD C. MEIER.

Witnesses:

EUGENE V. HEILMAN,

HENRY D. RANKIN.
